UNITED STATES PATENT OFFICE.

IVOR D. THOMAS, OF PALMYRA, OHIO, ASSIGNOR TO THE WELLMAN-SEAVIER-MORGAN COMPANY, OF CLEVELAND, OHIO, A CORPORATION OF OHIO.

RETORET CHARGER.

Application filed August 28, 1924. Serial No. 734,702.

To all whom it may concern:

Be it known that I, IVOR D. THOMAS, a citizen of the United States, residing at Palmyra, in the county of Portage and State of Ohio, have invented a certain new and useful Improvement in Retort Chargers, of which the following is a full, clear, and exact description.

This invention relates to retort chargers 10 of the type in which the retorts are charged from a hopper having an outlet adapted to deliver into the charging opening of the retort, and more particularly to chargers of the hopper car type adapted to travel along 15 a track above one or more rows of retorts and having one or more hoppers provided with outlets adapted to be positioned to deliver into the charging openings of the retorts.

20 In hoppers of the character referred to it is necessary that the lower end portion of the hopper adjacent the discharge gate be of sufficiently rigid construction to withstand the shearing action which takes place 25 when the gate is being closed against a stream of material discharging through the outlet, the impact of material falling from arches which form within the hopper during discharge of the material, and the abuse 30 incident to poking which is at times necessary to cause the material to discharge freely from the hopper.

For these reasons the discharge portions of such hoppers have heretofore been made 35 of castings and attached to the lower end of the body of the hopper which is usually constructed of sheet metal. In former constructions it has been a difficult matter to assemble and secure together the hopper body and discharge section due to the fact that the large tapered sheet metal bodies are liable to vary in size and are liable to be sprung more or less out of shape at the time when the casting section is attached thereto. 40 Furthermore the removal of such a discharge section and its replacement by a new casting was still more difficult.

It is the object of the present invention to provide a hopper construction in which the hopper body and discharge section may be assembled without difficulty and in which the discharge section may be readily removed and replaced by a new one.

More specifically it is the object of the invention to provide the hopper body and

the discharge section with independent supports by means of which they may be secured in such positions that the lower end of the hopper body projects into the discharge section, relative sizes of the interfitting parts of the body portion and discharge section being such that there is a clearance between the walls thereof sufficient to avoid any difficulty in assembly.

With the above and other objects in view, 60 the invention may be said to comprise the structure illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this 75 specification in which Fig. 1 is a top plan view of a charging car embodying the invention; Fig. 2 is an end elevation of the charging car; Fig. 3 is a side elevation of the charging car; Fig. 4 is a central vertical 80 section through the lower end of one of the hoppers; Fig. 5 is a side elevation of the lower end portion of one of the hoppers; Fig. 6 is a top plan view of the discharge section.

Referring to the accompanying drawings, 85 the charging car consists of an elongated frame 1 mounted on supporting wheels 2 which are disposed at right angles to the length of the frame and which are adapted to travel upon a track 3 which extends over the retorts to be charged. Mounted on the car in a row lengthwise of the frame 1 are a plurality of charging hoppers, the end hoppers 4 of which are substantially cylindrical while the intermediate hoppers 4^a are substantially oval in cross-section. Each of the hoppers has a tapered lower portion terminating in a discharge opening controlled by a gate 5, the hoppers being so formed that the discharge openings are regularly spaced. The gates 5 are of the usual type being suspended by arms 6 rigidly secured thereto and pivoted at their upper ends to the sides of the hopper, and these gates are 100 preferably provided with means by which they may be operated from a single convenient point on the car, the operating means consisting of links 7 connected to the gates 5 and operating connections from the links 7

to suitable operating handles 8 on an operator's platform 9 supported at one side of the frame 1.

The frame 1 consists of longitudinally extending sills or girders 10 connected at intervals by cross beams 11. Rigidly connected to the frame 1 and extending upwardly therefrom are posts 12 to the upper ends of which are connected upper girders 13 which are in turn connected at intervals by cross beams 14, the frame work being strengthened by suitably disposed diagonal braces 15. The sheet metal body portion 16 of each hopper is supported within the frame work extending upwardly from the main frame 1, the body portion 16 of the hopper being provided with outwardly projecting lugs 17 which rest upon the girders 13 and cross beams 14 and also with lugs 18 adjacent the lower ends thereof which rest upon adjacent cross beams 11.

The discharge section 19 is in the form of an integral casting which has a taper toward its lower end substantially the same as that of the lower end of the body portion 16. Adjacent its upper edge the section 19 is provided with integral attaching brackets 20 which engage the opposing faces of two adjacent cross beams 11 and are adapted to be bolted thereto. The discharge section 19 has a slightly enlarged upper portion 21 which receives the lower end of the sheet metal body portion 16 and this upper portion 21 of the discharge section has a diameter sufficiently greater than the discharge end of the body portion 16 to receive the body portion with a substantial clearance all the way around so that there will be no difficulty in positioning the discharge section 30 with respect to the body portion of the hopper. The body portion 16 of the hopper projects into the discharge section 19 a distance sufficient to provide a trap between the walls of the two sections of the hopper 45 of sufficient depth to prevent material working up through this clearance space and spilling over the top of the discharge section. Below the discharge end of the section 16 the discharge section 19 has a portion 50 22 which is offset inwardly with respect to the portion 21 and forms an extension of the tapered walls of the hopper. In order to provide convenient means for insuring a free flow of material from the hopper the upper portion of the discharge member 19 is provided with an internal channel 23 which provides an opening between the walls of the body portion of the hopper and the discharge section through which a poker may be inserted to dislodge any material which may block the flow through the outlet.

It will be readily appreciated that applicant has provided a construction which permits the casting discharge section to be applied to or removed from the hopper with

very little trouble. Furthermore, the wear upon the sheet metal portion of the hopper is much less due to the fact that the lower end portion thereof is free to vibrate under the impact of the material discharging from its lower end instead of being rigidly connected to the fixed casting.

Having described my invention, I claim:

1. A retort charger comprising a supporting frame, a hopper supported thereon consisting of a body portion and a discharge section mounted upon the frame independently of each other, said body portion tapering toward its lower end, the lower end of said body portion projecting into said discharge section.

2. A retort charger comprising a supporting frame, a hopper supported thereon, said hopper consisting of a body portion tapering toward its lower end and a discharge section forming a continuation of the body portion, said discharge section being rigidly supported on the frame and said body portion being supported on the frame independently of the discharge section with its lower end projecting into said discharge section, there being a clearance between the walls of said body portion and discharge section.

3. A retort charger comprising a car having a frame, a hopper supported on said frame, said hopper comprising a body portion the lower part of which is tapered and a tapered discharge section supported independently of the body portion and receiving the lower end of the body portion, the upper end of the inclined wall of the discharge section surrounding the lower end of the body portion and spaced outwardly therefrom.

4. A retort charger comprising a car having a frame, a hopper supported on said frame, said hopper comprising a sheet metal body portion rigidly supported on the frame and having a downwardly tapering lower end, and an independently supported discharge section rigidly secured to the frame independently of the body portion and receiving the lower end of the body portion.

5. A retort charger comprising a frame, a hopper supported on said frame, said hopper consisting of a sheet metal body portion rigidly supported on the frame, and a tapered discharge section comprising a casting rigidly secured to the frame independently of the body portion and of greater transverse dimensions at its upper end than the lower end of said body portion, the lower end of said body portion projecting into said discharge section, and a gate carried by said discharge section.

6. A retort charger comprising a frame, a hopper supported on said frame, said hopper having a body portion rigidly mounted on the frame and a discharge section fixed to the frame independently of said body

portion, said discharge section being of greater transverse dimensions than said body portion and having the upper end portion of its wall surrounding the lower end of said body portion and spaced outwardly therefrom, and a discharge gate carried by the discharge section.

5 7. A retort charger comprising a frame, a hopper carried by said frame, said hopper comprising a body portion and a tapered discharge section rigidly supported on the frame independently of the body portion, the lower end of said body portion projecting into said discharge section, the wall of 10 said discharge section being spaced from the body portion to provide a clearance space through which a poker may be inserted, and a discharge gate carried by said discharge section.

15 8. A retort charger comprising a frame, a hopper carried by said frame, said hopper consisting of a sheet metal body portion supported on the frame and having a tapered lower end and a discharge section comprising a one piece casting having a 20 tapering wall surrounding and spaced outwardly from the lower end of said body portion, and a discharge gate carried by said discharge section.

25 9. A retort charger comprising a frame,

a hopper carried by said frame, said hopper consisting of a sheet metal body portion mounted on said frame and tapering toward its lower end and a discharge section comprising a one piece casting formed with a 30 tapering wall and secured to the frame independently of the body portion, the wall of said discharge section surrounding the lower end of said body portion and having a channel formed therein through which a poker 35 may be inserted, and a discharge gate carried by said hopper.

10 10. A retort charger comprising a supporting frame and a hopper carried by said frame, said frame having upper and lower 40 hopper supporting girders, said hopper consisting of a body portion which tapers toward its lower end and a discharge section forming a continuation of the body portion and correspondingly tapered, said discharge 45 section being rigidly secured to the lower girders of the frame, and said body portion having supporting lugs engaging with the upper girders to support the said body portion with its lower end projecting into said 50 discharge section.

In testimony whereof, I hereunto affix my signature.

IVOR D. THOMAS.
